UNITED STATES PATENT OFFICE

98,524

DESIGN FOR A FREEZING DEVICE FOR EDIBLES

Fred H. Kaup and Floyd H. Kinyoun,
Omaha, Nebr.

Application April 19, 1935, Serial No. 56,472

Term of patent 14 years

To all whom it may concern:

Be it known that we, Fred H. Kaup and Floyd H. Kinyoun, citizens of the United States, residing at Omaha, in the county of Douglas and State of Nebraska, have invented a new, original, and ornamental Design for a Freezing Device for Edibles, of which the following is a specification, reference being had to the accompanying drawing, forming a part thereof.

Figs. 1 and 2 of the drawing are perspectives of a freezing device, showing our new design.

We claim:

The ornamental design for a freezing device for edibles, substantially as shown.

Signed at Omaha, Nebraska, this 2 day of February, A. D., 1935.

FRED H. KAUP.
FLOYD H. KINYOUN.
